[57] CLAIM

The ornamental design for a vehicle guidance device, as shown and described.

DESCRIPTION

FIG. 1 is a perspective view of a vehicle guidance showing my new design, it being understood that the broken lines are for illustrative purposes only and form no part of the claimed design;

FIG. 2 is a rear side view thereof of one member of the vehicle guidance device;

FIG. 3 is a left side view thereof;

FIG. 4 is a front side view thereof;

FIG. 5 is a right side view thereof;

FIG. 6 is a bottom view thereof;

FIG. 7 is a top view thereof;

FIG. 8 is a rear side view thereof of the second member of the vehicle guidance device;

FIG. 9 is a right side view thereof;

FIG. 10 is a front side view thereof;

FIG. 11 is a right side view thereof;

FIG. 12 is a bottom view thereof; and,

FIG. 13 is a top view thereof.
